HUDSON MOTOR CAR COMPANY, OF DETROIT, MICHIGAN, A CORPORATION OF
MICHIGAN

HINGE

Application filed September 19, 1927. Serial No. 220,422.

This invention relates especially, although not exclusively, to hinges for the doors of closed automobile bodies and has for its object to provide a hinge of simple construction and inconspicuous appearance which will afford adequate support against sagging of the door, which is without sharp projecting parts likely to come into contact with and cause injury to the person or clothing of the user of the car, in which the knuckles or pintle pin bearings are fully covered at the outer side of the body, and which will preserve its finish indefinitely without deterioration.

The foregoing and other objects of the invention will best be understood from the following description of certain forms or embodiments thereof illustrated in the accompanying drawings. It will be understood that the particular constructions described and shown, and which have been chosen for purposes of exemplification, are susceptible of considerable variation within the scope and spirit of the invention as defined by the claims hereunto appended.

The invention will be more clearly understood from the following description in conjunction with the accompanying drawings; in which,

Fig. 1 is a fragmentary perspective view of a portion of an automobile body having a door hung on a hinge embodying the invention;

Fig. 2 is a sectional plan view taken through the pintle pin bearing 26;

Fig. 3 is a fragmentary perspective view of the hinge member 24 as viewed from the right of Fig. 2;

Fig. 4 is an elevational view of the same as viewed from the left of Fig. 2;

Fig. 5 is a sectional view taken on the line 5-5 of Fig. 4;

Fig. 6 is a sectional view taken on the line 6-6 of Fig. 4;

Fig. 7 is an elevational view of the hinge member 25 as viewed from the right of Fig. 2;

Fig. 8 is a sectional view taken on the line 8-8 of Fig. 7;

Fig. 9 is a sectional plan view taken through the pintle pin bearing 27.

In Fig. 1 is shown a portion of a closed automobile body having a side sill 15, side paneling 16, and a door designated as a whole by the numeral 17. The paneling 16 is secured in any suitable manner at its forward edge to a vertical door post or body hinge pillar 19. In the construction shown, the side of the body, as determined by the shape of the paneling 16 and pillar 19, is of curved form, having a sweep-in at the bottom. As shown, the door 17 includes a door hinge pillar 20 having door paneling 21 secured thereto. The parts above referred to are herein shown as composed of sheet metal, although specifically, and except as hereinafter pointed out, the construction of these parts, and the material of which they are composed, are immaterial.

In accordance with the present invention, the door 17 is connected to the body hinge pillar 19 by a hinge designated as a whole in Fig. 1 by the numeral 22. Preferably, and as shown in said figure, the hinge 22 extends continuously from the point adjacent the top of the door and body hinge pillar to a point adjacent the bottom of said parts, being substantially straight and vertical throughout its length to provide an axis upon which said door may swing, said axis being located immediately adjacent the body parts at the point of the maximum width of the body as determined by the curvature of the latter, and being spaced therefrom at points of less width, particularly opposite the bottom sweep-in of the body. The hinge 22 comprises two hinge members 24 and 25 having pintle pin bearings 26 and 27 respectively, successive pintle pin bearings 26 and 27 being in engagement with one another throughout the length of the hinge, and being connected by a straight pintle 28 extending through all of said bearings.

The hinge member 24 is formed, preferably, from a single piece of sheet material, such as stainless steel or even common steel, a portion of which is curved throughout the length of the member into a substantially semi-cylindrical shape to form a cover. Extending from the free edge of the cover so formed are a plurality of spaced projections which

are rolled toward the cover within the same to form the pintle pin bearings 26. Preferably, the lateral extensions are inwardly offset substantially in line with the free edge of the cover and are rolled thereunder to bring their edges substantially in contact with the offset as shown in Fig. 3. In this manner a continuous hinge member is provided having a plurality of spaced pintle pin bearings 26 and a cover 29 forming an integral part thereof and extending therebetween as best shown in Fig. 3. The other hinge member 25 may be formed in any suitable manner to provide a plurality of pintle pin bearings 27 adapted to fit between the pintle pin bearings 26 and within the cover 29. Preferably, the hinge member 25 is formed from a blank of sheet material of thinner gauge than that used in forming hinge member 24 and is folded upon itself (as shown in Fig. 8) to provide spaced pintle pin bearings. The hinge members 24 and 25 may be secured to the door hinge pillar 20 and the body hinge pillar 19 in any suitable manner, as by rivets 30, and are assembled by positioning the pintle pin bearings 27 between the bearings 26 and within the cover 29 and are secured in place by the pintle pin 28.

Preferably, and as shown in Fig. 9, the hinge member 25, or at least the portion thereof which forms the pintle pin bearings 27, is formed of thinner stock than the pintle pin bearings of the member 24, the bearings of both members being of the same internal diameter to receive the pintle pin 28. A clearance is accordingly provided between the exterior surfaces of said bearings 27 and the interior surface of the cover portion of the member 24 within which they turn, thereby permitting said exterior surfaces to be provided with an enamel or other finish which will not be destroyed in use.

The provisions of the invention make possible the use of a lighter material inasmuch as the hinge extends from a point adjacent the top to a point adjacent the bottom of the door and the edges of the alternate pintle pin bearings interengage through the length of the hinge. The cover of the hinge is an integral part of one of the hinge members and serves to impart great rigidity thereto. In prior hinge constructions it has been necessary to use a stainless material, such as stainless steel, whereas, the construction of the hinge of the invention is such as to permit the use of common steel. In spite of these advantages, the hinge may be manufactured at low cost and presents a neat appearance. It will be seen that not only is the hinge member 24 constructed with pintle bearings 26 providing a straight preferably vertical axis about which the door swings, but said hinge member 24 is also provided with an attaching portion enabling it to be mounted

on a curve corresponding to the curvature of the body while permitting the door to swing about a vertical axis. Accordingly, in the present instance, the female hinge member 24 is stamped with longitudinal offset portions 24a and 24b attachable to correspondingly shaped portions of the door pillar 20 (see Figs. 2 and 9).

Referring to Fig. 4 it will be seen that the flange portion 24a is curved or convex in the length of the hinge member, the longitudinal bends 40 and 41 being formed on curved lines. This construction therefore enables the hinge to conform to the convex door while supporting the same to swing on a vertical axis.

What we claim is:

1. A hinge for automobile doors and the like, said hinge comprising two members connected by a pintle pin, one of said members having a curved portion extending the length of said member and forming a cover and a plurality of projections extending from the free edge of said cover and inwardly offset therefrom in line with said free edge by an amount substantially equal to the thickness of the material and thence rolled toward the cover with their ends substantially meeting the offset to form a plurality of spaced pintle pin bearings within said cover, and the other of said members having a series of pintle pin bearings fitting between said first named pintle pin bearings within the cover.

2. A hinge for automobile doors and the like, said hinge comprising two members connected by a pintle pin, one of said members having a curved portion extending the length of said member and forming a cover and a plurality of spaced pintle pin bearings within said cover, and the other of said members having a series of pintle pin bearings fitting between said first named pintle pin bearings within the cover, said last named pintle pin bearings being of thinner stock than said first named pintle pin bearings, whereby clearance is provided between them and said cover.

3. A hinge for automobile doors and the like, said hinge comprising two members connected by a pintle pin, one of said members having a curved portion extending the length of said member and forming a cover and a plurality of projections extending from the free edge of said cover and inwardly offset therefrom and thence rolled toward the cover to form a plurality of spaced pintle pin bearings within said cover, and the other of said members having a series of pintle pin bearings fitting between said first named pintle pin bearings within the cover, said last named pintle pin bearings being of thinner stock than said first named pintle pin bearings, whereby clearance is provided between them and said cover.

4. In a hinge for automobile doors and the like, a female hinge member having a curved

portion at one edge forming a cover, and a plurality of projections extending from the free edge of said cover and coiled toward the cover to form a plurality of spaced pintle pin bearings within said cover, said projections being inwardly offset in line with said free edge by an amount substantially equal to the thickness of the metal, the ends of the coiled projections terminating adjacent said offset.

5. A hinge for an automobile door comprising a pair of hinge members each having pintle pin bearings, a pintle pin connecting said bearings, one of said hinge members being 10 formed of thinner stock to provide clearance between the members.

6. In a hinge for automobile doors and the like, a female hinge member having at one side a plurality of projections each coiled or 15 rolled into a complete convolution forming a pintle pin bearing with the free edge of the convolution covered by the body of the hinge member, said bearing being offset inwardly on a line parallel to said free edge by an 20 amount substantially equal to the thickness of the metal.

7. In an automobile body, in combination, a door provided with an outwardly curved or convex panel, a hinge member extending 25 continuously substantially the major distance in the height of the door, and comprising a sheet metal plate having its outer edge rolled inwardly against the face of the plate to form a series of vertically aligned tubular bearings 30 to receive a pintle pin, said plate adjacent its opposite edge having a flat vertical attaching portion and being formed intermediate said portion and bearings with an angular flange portion curving inwardly 35 from the lower pintle pin bearings in the line of curvature of the door panel and engaging the inner face thereof.

8. In a hinge, a hinge member formed with a curved cover portion, pintle pin bearings 40 extended from the metal of the cover portion and located partly within the cover portion, the metal of the bearings being offset inwardly on a line adjacent the line of free edges of the cover portion to dispose the inner 45 face of the offset portion in a circle concentric with the axis of the pintle pin.

9. In a hinge, a hinge member having a curved cover portion, pintle pin bearings 50 extended from the metal of the cover portion and disposed partly within the latter, the metal of the bearings being inwardly offset in line with the free edges of the cover portion to conform to the cylindrical shape of a pintle pin.

10. In testimony whereof we affix our signatures.

MILLARD H. TONCRAY.
JAMES W. GREIG.
